UNITED STATES PATENT OFFICE

2,594,884

BAILING TOOL AND THE LIKE

Joseph F. Dornacher, Osage, Wyo.

Application September 20, 1947, Serial No. 775,299

5 Claims. (Cl. 166—19)

1

The invention relates to tools for removing loose material from holes drilled in the earth for oil wells, gas wells, water wells, and the like, and the present invention includes improvements of the invention set forth in my prior U. S. Letters Patent No. 1,786,152, issued December 23, 1930.

The bailing tool of my said U. S. Patent No. 1,786,152 includes a relatively long tubular trepanning drill having walls forming a continuous unobstructed passageway from end to end thereof, there being an enlargement of the passageway intermediate and spaced from the ends thereof, and there being an opening in the side wall of the tubular trepanning drill intermediate and spaced from the ends thereof and adjacent and communicating with the enlargement. A gate member is pivotally mounted on the tubular member for normally covering the side opening, and a closure member is pivotally mounted on the inner face of the gate member for movement within the enlargement and passageway. There is a seat in the walls at the intersection of the enlargement and tubular passageway, and the closure member swings from one position within the enlargement on the seat for entirely closing off the continuous passageway to another position within the enlargement away from the seat permitting free passage of material being bailed through the passageway. The gate member is adapted to be swung away from its normal position closing the side opening to a position in which the closure member is withdrawn from the enlargement through the side wall opening. Latch means are also provided on the gate member for coacting with a second side opening in the tubular drill to maintain the gate member in closed position during the drilling operations.

When the bailing tool of my said U. S. Patent No. 1,786,152 is filled, a load of cavings has been built up in the pipe to the lower end of which the upper end of the trepanning drill is secured, and the closure member is extended across the lower end of the passageway of the drill, resting on the seat and under the pressure of the cavings sometimes mixed with water and gas which have been collected in the upper pipe.

The gate is likewise subject to this pressure, and in certain instances the pressure of the load collected in the pipe above the closure and gate has been so great that it has jammed the latch or lock on the outwardly swinging upwardly hinged gate, making it very difficult to open the latch and swing out the gate and the attached closure from beneath the load collected in the upper pipe of the bailing tool.

2

The objects of the present improvements include the provision of a bailing tool having the general characteristics of the bailing tool of my said U. S. Patent No. 1,786,152, but having an improved structure and arrangement of parts whereby the closure for the passageway of the trepanning drill may be quickly and easily removed, despite any pressure due to the collected load in the upper pipe of the tool.

10 Further objects of the present improvements include the provision of improved lock means and lock operating and handling means for a door for a side opening in such a bailing tool.

Further objects of the present improvements 15 include the provision of improved bumper means whereby the closure for the drill passageway may retract into a recess at one side of the passageway to permit the passage of a large rock or other material substantially the size of the passageway, 20 and to provide for springing back of the closure into the passageway after the rock or other material has passed by.

Further objects of the present improvements 25 include the provision of a bailing tool having the general characteristics of the bailing tool of my said U. S. Patent No. 1,786,152, and having a simplified construction and arrangement of parts whereby the improved bailing tool may be easily and economically manufactured, used, and maintained.

30 The foregoing and other objects are attained by the bailing tool and the like, combinations, sub-combinations, and parts, which comprise the present invention, the nature of which is set forth in the following general statement, and preferred 35 embodiments of which together with their mode of use are set forth by way of example in the following description, and which are particularly and distinctly pointed out and set forth in the appended claims forming part hereof.

40 The nature of the present invention may be stated in general terms as including in a bailing tool and the like, a relatively long tubular trepanning drill member, the upper end of which is connected to the lower end of a pipe, and in one 45 side of the tubular member there is formed an opening in which is removably mounted by improved means a door on the upper end of which is hinge connected the lower end of a dart or inverted spoon which is adapted to swing from one position permitting passage of material through the tubular member to another position 50 providing a closure for the passageway of the tubular member, the door and the dart or spoon

3

being removable through the side opening for permitting unloading of the bailing tool.

There is also preferably provided an improved removable key and handle for the door by means of which the lock for the door may be operated and the door and spoon removed together from the side opening.

Preferred embodiments of the improved bailing tool and the parts thereof are illustrated in the accompanying drawing forming part hereof, in which:

Figure 1 is a fragmentary view with portions in section, illustrating the improved bailing tool hereof in use in a drill hole;

Fig. 2 is an enlarged longitudinal axial sectional view of the improved bailing tool hereof, illustrating the dart or spoon in full lines effecting a closure in the passageway of the tubular drill member, and in dot dash lines illustrating the dart or spoon in position permitting passage of material through the passageway;

Fig. 3 is a fragmentary view similar to Fig. 2 illustrating the side opening in the tubular drill member, and with the door for the side opening and the dart or spoon removed;

Fig. 4 is an elevation view with portions in section illustrating the door and dart or spoon removed from the side opening of the tubular drill member, and showing the improved handle and lock operating key in place in the door;

Fig. 5 is an elevation view showing the outside of the door and the spoon removed from the opening in the tubular drill member, portions of the door being shown broken away and in section for illustrating the lock for the door;

Fig. 6 is a view looking in the direction of the arrows 6—6 of Fig. 5 showing the lower portions of the door; and

Fig. 7 is a fragmentary view with portions broken away and shown in section, illustrating details of the door handle and lock operating key.

Similar numerals refer to similar parts throughout the several views of the drawing.

The improved bailing tool is indicated generally by 10 and includes a tubular trepanning drill member 11, sometimes known as a shoe, and having a continuous passageway from end to end thereof. Within the passage of the tubular drill member 11 there is operatively mounted an improved automatic closure 12, sometimes known as a dart or spoon, and which is located above the preferably ground angled peripheral lower cutting edge 13 of the tubular drill member 11.

There is formed in one side of the tubular drill member 11 an opening 14 which has a flat upper edge 15 and a curved lower edge 16 and a door indicated generally by 17 is removably mounted in the opening 14, the lower end of the closure member 12 having a horizontal hinge connection 18 with the upper end of the door 17. Within the passageway of the tubular drill member 11 opposite and above the door 17 there is formed a ledge 19 upon which the dart or spoon 12 seats when in the closed position shown in Fig. 2. Opposite the seat 19 there is formed in the passageway of the tubular drill member 11 a recess 20 into which the dart or spoon 12 may swing upwardly when being loaded with cavings as shown in Fig. 1.

There is preferably provided a rubber bumping nipple 21 extending from the top face of the dart or spoon 12 for urging the dart or spoon 12 from the upper position permitting passage of material through the passageway of the tubular drill

4

member 11 as shown in Fig. 1 in full lines and dot-dash lines in Fig. 2 to the position closing the passageway of the tubular drill as shown in full lines in Fig. 2, in which position the dart or spoon 12 carries a load of any cavings or other material which have passed above it in the use of the improved bailing tool 10.

The improved bailing tool 10 is secured as by means of a collar 22 to the lower end of a pipe 23, the internal diameter of the pipe 23 being substantially equal to the inside diameter of the tubular drill member 11, and the external diameter of the tubular drill 11 and pipe 23 being only slightly less than the internal diameter of the drill hole 24.

The upper end of the pipe 23 is secured as by a coupling 25 to the lower end of a relatively short connecting pipe 26 which is preferably provided with side openings 27 through which excess material may escape. The connecting pipe 26 may be provided at its upper end as shown with a bail 28 which may be connected to a drill line 29, or the connecting pipe may be secured by well known means to a set of jars hung upon the drill line as may be desired.

As shown and preferably the door 17 includes a rear plate 30 and a front plate 31 separately secured to each other by screws 32. The upper flat edge of the rear plate 30 is provided with an upwardly opening notch 33 which receives a hinge tongue 34 extending downwardly from the lower edge of the dart or spoon 12. The hinge tongue 34 has formed therein a hinge bore 35 which receives the hinge pin 36 having ends extending from opposite sides of the hinge tongue 34 and fitting into recesses formed in the front face of the door rear plate 30. The door front plate 31 has a central upwardly extending retaining tongue 37 overlapping the hinge tongue 34 and the hinge pin 36 in the assembled arrangement of the door 17 and the spoon 12.

For providing improved lock or latch means for the door 17 there is formed a recess 38 in the front face of the door back plate 30 and a rotary latch 39 is located in the recess 38 and overlapped by the door front plate 31 and rear portions of the door back plate 30, and the rotary latch 39 has a forward trunnion 40 journaled in a suitable cylindric opening in the door front plate 31 and a similar rear trunnion 41 journaled in a suitable opening in the door back plate 30. The latch plate 39 and its trunnions 40 and 41 have formed therein a square opening 42.

The latch plate 39 is generally cylindric and includes an outwardly extending latch tongue 43 opposite to which it has formed in its periphery a detent 44. A spring pressed plunger 45 mounted between the door back plate 30 and door front plate 31 is arranged so that its outer end extends into the detent 44 when the latch plate 39 is rotated to the latching position as shown in Fig. 2.

The upper end portions 46a and 46b of the door back plate 30 extend above the upper edge of the door front plate 31 and are arranged to extend back of and engage the flat upper edge 15 of the opening 14 in the tubular drill member 11 when the door 17 and spoon 12 are assembled in the tubular drill member 11 as shown in Fig. 2, and at the same time the latch tongue 43 is rotated into a retaining groove 47 formed centrally in the lower edge 16 of the door opening 14 in the tubular drill member 11.

Separable door handle and lock operating key means for holding the door during and after re-

removal and for operating the lock or latch are indicated generally by 50 and include a stub shaft 51 having a square inner end 52 shaped to fit the square opening 42 in the latch plate 39 and its trunnions 40 and 41, and from the outer end of the stub shaft 51 there extends an operating handle 53. The stub shaft 51 has formed therein a bore in which is journaled a shank 54 having an enlarged square inner head 55 which is the same size as the square inner end 52 of the stub shaft 51. On the outer end of the shank 54 there is secured a turning wing 56. Accordingly, when, as shown in Fig. 7, the square head 55 has its sides aligned with the square inner end 52 of the stub shaft 51, both the square head 55 and the square inner end 52 of the stub shaft 51 may be inserted into the square opening 42 of the latch plate 39 and its trunnions 40 and 41, after which the wing 56 may be turned, turning the square head 55 to the position shown in Fig. 4, thereby securing the handle and lock operating key means 50 in the door 17.

Accordingly, after the improved bailing tool 10 has been filled with cavings, and elevated from the drill hole, and moved to one side, the square head 55 and square inner end 52 of the door handle and lock operating key means 50 may be inserted into the square opening 42 of the latch plate 39 and its trunnions, the wing 56 may be turned to turn the square head 55 to engage the inner face of the trunnion 41 as shown in Fig. 4, whereupon the handle 53 may be turned to disengage the latch tongue 43 from the groove 47, and the door 17 and the attached dart or spoon 12 may be moved from the tubular drill member 11 permitting the load of material in the bailing tool 10 to drop out.

When the handle 53 is thus locked in the door 17 having the attached dart or spoon 12, these parts become a unitary structure which is bodily removable from the tubular drill member 11.

By the foregoing construction and arrangement of the door opening 14 in the tubular drill member 11, the door 17, the spoon 12, the lock means on the door, and the handle and lock operating key means 50, regardless of the pressure on the spoon 12 when in the closed position as shown in Fig. 2, by a load of cavings, water and possibly gas above the spoon 12, the door 17 and the spoon 12 may be easily and quickly removed from and through the door opening 14.

The embodiments of the present invention illustrated and described herein are by way of example, and the scope of the present invention is not limited to the same or to the particular details thereof but is commensurate with any and all novel subject matter contained herein which may at any time properly under the United States patent laws be set forth in the claims hereof or originating herein, and the elements of any such claims are intended to include their functional or structural equivalents.

I claim:

1. In a tool for bailing and the like, a tubular member having walls forming a passageway from end to end thereof, one of the walls of the tubular member having an opening formed therein intermediate and spaced from the ends thereof, the opening having an upper edge, a door removably fitting in the opening and being bodily removable from the opening and the tubular member and the door having an upper end extending back of and engaging the upper edge of the opening, a closure member having a lower end, hinge means connecting the lower end of

the closure member with the upper end of the door, the closure member being located in the passageway when the door is in the opening and the closure member being swingable in the passageway and shaped to close the passageway when swung to one position and open the passageway when swung to another position, and means operative on the lower end of the door for releasably locking the door in the opening.

2. In a tool for bailing and the like, a tubular member having walls forming a passageway from end to end thereof, one of the walls of the tubular member having an opening formed therein intermediate and spaced from the ends thereof, the opening having a flat upper edge, a door removably fitting in the opening and being bodily removable from the opening and the tubular member and the door having a flat upper end extending back of and engaging the upper edge of the opening, a closure member having a lower end, hinge means connecting the lower end of the closure member with the upper end of the door, the closure member being located in the passageway when the door is in the opening and the closure member being swingable in the passageway and shaped to close the passageway when swung to one position and open the passageway when swung to another position, and means operative on the lower end of the door for releasably locking the door in the opening.

3. In a tool for bailing and the like, a tubular member having walls forming a passageway from end to end thereof, one of the walls of the tubular member having an opening formed therein intermediate and spaced from the ends thereof, the opening having an upper edge, a door removably fitting in the opening and being bodily removable from the opening and the tubular member and the door having an upper end extending back of and engaging the upper edge of the opening, a closure member having a lower end, hinge means connecting the lower end of the closure member with the upper end of the door, the closure member being located in the passageway when the door is in the opening and the closure member being swingable in the passageway and shaped to close the passageway when swung to one position and open the passageway when swung to another position, and means on the lower end of the door for releasably locking the door in the opening.

4. In a tool for bailing and the like, a tubular member having walls forming a passageway from end to end thereof, one of the walls of the tubular member having an opening formed therein intermediate and spaced from the ends thereof, the opening having an upper edge, a door removably fitting in the opening and being bodily removable from the opening and the tubular member and the door having an upper end extending back of and engaging the upper edge of the opening, a closure member having a lower end, hinge means connecting the lower end of the closure member with the upper end of the door, the closure member being located in the passageway when the door is in the opening and the closure member being swingable in the passageway and shaped to close the passageway when swung to one position and open the passageway when swung to another position, and means on the lower end of the door for releasably locking the door in the opening, and handle and key means connected with the locking means for operation thereof and for carrying the door and closure member away from the opening.

5. In a tool for bailing and the like, a tubular member having walls forming a passageway from end to end thereof, one of the walls of the tubular member having an opening formed therein intermediate and spaced from the ends thereof, the opening having an upper edge, a door removably fitting in the opening and being bodily removable from the opening and the tubular member and the door having an upper end extending back of and engaging the upper edge of the opening, a closure member having a lower end, hinge means connecting the lower end of the closure member with the upper end of the door, the closure member being located in the passageway when the door is in the opening and the closure member being swingable in the passageway and shaped to close the passageway when swung to one position and open the passageway when swung to another position, and means on the lower end of the door for releasably locking the door in the opening, and handle and

key means adapted for connection with the locking means for operation thereof and for carrying the door and closure member away from the opening, and releasable means for securing the handle and key means in the locking means.
